UNITED STATES PATENT OFFICE.

WILLIAM L. McGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed February 10, 1921. Serial No. 443,772.

To all whom it may concern:

Be it known that I, WILLIAM L. McGRATH, a citizen of the United States, residing at Elmira, in the county of Chemung 5 and State of New York, have invented certain new and useful Improvements in Engine Starters, of which the following is a specification.

My invention relates to a drive or transmission for a starter for an engine, such as an internal combustion engine, and the object thereof is to improve the structure and mode of operation of a certain type of such a drive characterized by a rotatable shaft 10 on which a driving member or pinion is mounted for free longitudinal and rotary movement thereon, and also for rotary movement therewith and, when in engagement with a member of the engine, such as 15 the flywheel thereof, adapted to be clamped to the rotatable member or shaft by means of a control member or nut having an automatic longitudinal movement therewith. Speaking in general terms, the improvement 20 consists in providing a drive of this type with positive clutch means, of novel construction and operation, between the driving member and the control member.

Moreover, my structure is such that in 25 case of any stoppage of the pinion at a point intermediate its length of longitudinal movement (as for instance when the pinion and flywheel abut end to end), the consequent jamming action will be automatically relieved by releasing the pressure of the control member against the pinion and thereby releasing the pressure of the pinion against the flywheel.

In the drawing Fig. 1 is a plan view partly 30 in section embodying my invention; Fig. 2 a detail view on a larger scale illustrating co-operating parts of the driving member and the control member; Fig. 3 a section on the irregular lines 3-3 of Fig. 2; Fig. 4 a 35 section on the line 4-4 of Fig. 5; Fig. 5 an elevation of one end of the driving member; Fig. 6 an elevation of one end of the control member and Fig. 7 a section on the line 7-7 of Fig. 6.

In the present instance I have shown one embodiment of my invention incorporated in a drive of a specific character and of the single reduction, and also the outboard va-

riety, but it will be understood that my invention may be embodied in other constructions and also in the varieties known as the double reduction and the inboard.

Referring to the embodiment herein illustrated, the prime mover, which is an electric motor indicated at 1, is provided with an 55 extended armature shaft 2 on which is mounted a shaft in the form of a sleeve provided with a screw threaded portion 3 and a smooth portion 4, such shaft being provided at its outer end with a stop 5. This 60 shaft is provided with a head 6 operatively connected with the shaft 2 through the driving head or collar 7 secured to such shaft by the stud 8 and through a yielding driving connection such as the drive spring 9, 70 whose opposite ends are anchored respectively to the stud 8 and to the stud 10, the latter being secured to the head 6.

Upon the screw shaft there is mounted for free movement a driving member which is in 75 the form of a pinion 11 adapted to engage or mesh with a member of the engine to be started, such as with the teeth 12 of the flywheel 13. This pinion is held in its normal position, shown in Fig. 1, by a yielding 80 means such as the spring 14 and the longitudinally movable collar 15 interposed between the pinion and such spring.

The pinion 11 is provided at one end with a disk 16 having contact surfaces 17, and 85 also transverse grooves 18.

The control member is here in the form of a nut 19 threaded unto the threaded portion 3 of the screw shaft whereby the same has an automatic longitudinal movement when such 90 shaft is rotated. This nut is provided with a disk 20, having adjacent to the disk 16 contact surfaces 21 and also two ribs 22 adapted to co-operate with the grooves 18. The sides of the grooves 18 are straight, being made by transverse cut diametrical of the pinion. The sides 23 of the ribs 22 converge outwardly, with the result that when the grooves and ribs are co-operating as a positive clutch the sides of the ribs and the 95 sides of the grooves constituting the driving faces of the clutch are in full contact. Moreover, the grooves are materially wider than the ribs, and furthermore, by preference, the grooves are slightly greater in depth than 100 the thickness of the ribs as shown in Fig. 2,

so that the contact surfaces 17 and 21 of the pinion and nut will take the thrust of the screw action of the nut.

Describing the cycle of operation and starting with the parts in their normal position shown in Fig. 2, when the motor is operated the screw shaft is rotated with the result that the nut 19 is automatically moved longitudinally to the left along the screw threaded portion of the shaft, carrying the pinion longitudinally in the same direction because of the contact of the disks 16 and 20. In this longitudinal movement the pinion is meshed with the flywheel and after 15 the collar 15, and consequently, the pinion has been arrested in its longitudinal movement by the stop 5, such pinion will be clamped to the sleeve shaft by the screw action of the nut. In the event that the 20 grooves and ribs are at this time already in co-operative relationship, the nut will move rotarily slightly until the sides of the grooves and ribs contact in driving relationship, whereupon the pinion will partake of 25 the rotary movement of this shaft and the engine will be rotated. In the event that the grooves and ribs are at such time not in co-operating relationship and in the event further of considerable resistance from the 30 flywheel, the nut will move angularly until such grooves and ribs register, whereupon a positive clutch is established between the pinion and the nut, whereupon the pinion will be rotated by its shaft and the flywheel, 35 consequently, rotated. After the engine starts on its own power the nut will be returned to the normal position shown in Fig. 1 by reason of its excess of speed (imparted to it from the flywheel through the medium 40 of the pinion) over that of the screw shaft and the pinion will be demeshed and returned to normal position by the spring 14.

In case of the abutting of the pinion against the flywheel when the teeth thereof 45 do not register and therefore do not mesh, the torque will continue to be transmitted from the motor to the drive until a stall torque is reached whereupon the motor will stop. The current being thereupon cut off 50 from the motor at the switch 24, the stored up energy in the drive spring will revolve the motor armature and consequently the shaft in a reverse direction. This reverse rotation is imparted to the control member 55 whose ribs will be moved away from the driving face of the grooves and caused to hit somewhat forcibly against the opposite face of the grooves, thereby stopping the rotary movement of the control member 60 with the shaft and also breaking loose the frictional connection between the teeth of the shaft and control member. As a result, the control member is moved backwardly 65 longitudinally by reason of the continued backward rotation of the shaft and the

pressure of the control member against the driving member and the pressure of the latter against the flywheel will be released. Thus the parts automatically resume a position for normal functioning.

I claim:

1. An engine starter drive including a rotatable driving shaft, a driving member mounted for free movement longitudinally thereof, a control member mounted for automatic longitudinal movement thereof and rotary movement therewith, and clutch means adapted to operatively connect the two members for positive driving when the driving member is stopped in its longitudinal movement, said two members being capable of free angular movement when they are in normal position.

2. An engine starter drive including a rotatable driving shaft, a driving member mounted for free movement longitudinally thereof, a control member mounted for automatic longitudinal movement thereof and rotary movement therewith, said two members having complementary contact surfaces and also positive clutch means, whereby such control member may clamp the driving member to the shaft after it has stopped in its longitudinal movement, said two members being capable of free angular movement when they are in normal position.

3. An engine starter drive including a rotatable screw shaft, a driving member mounted for free movement longitudinally thereof, and a control member threaded on the shaft for automatic longitudinal movement thereof and rotary movement therewith, said control member in its longitudinal movement being adapted to contact the driving member and by its screw action on the shaft, to clamp the latter to the shaft for rotary movement therewith when such driving member is stopped in its longitudinal movement, said driving and control members being provided with positive clutch means which operate under the condition of excessive resistance from the engine member, said two members being capable of free angular movement when they are in normal position.

4. An engine starter drive including a rotatable screw shaft, a driving member mounted thereon for free movement longitudinally thereof, and a control member threaded on the shaft for automatic longitudinal movement thereof and rotary movement therewith, said driving member having a free longitudinal movement with respect to the control member and said control member in its longitudinal movement being adapted to contact the driving member and by its screw action on the shaft, to clamp the latter to the shaft for rotary movement therewith when such driving member is

stopped in its longitudinal movement, said driving and control members being provided with positive clutch means which operate under the condition of excessive resistance
5 from the engine member, said clutch means comprising a groove in one of said members and a cooperating rib in the other member, said two members being capable of free angular movement when they are in normal
10 position.

5. An engine starter drive including a rotatable shaft, a driving member mounted for free movement longitudinally thereof, and a control member mounted for automatic longitudinal movement thereof and rotary movement therewith, said control member in its longitudinal movement being adapted to contact the driving member and clamp the latter to the shaft for rotary movement therewith when such driving member is stopped in its longitudinal movement, said driving and control members having an unlimited angular movement, one with respect to the other, until the driving member is so stopped in its longitudinal movement and having means for thereafter limiting such angular movement.

6. An engine starter drive including a rotatable shaft, a driving member mounted for free movement longitudinally thereof, and a control member mounted for automatic longitudinal movement thereof and rotary movement therewith, said control member in its longitudinal movement being adapted to contact the driving member and clamp the latter to the shaft for rotary movement therewith when such driving member is stopped in its longitudinal movement, said driving and control members having an unlimited angular movement, one with respect to the other, until the driving member is so stopped in its longitudinal movement and having means for thereafter limiting such angular movement, said means comprising a groove in one of said members and a cooperating rib in the other member, said groove being considerably wider than said rib.

7. An engine starter drive including a rotatable shaft, a driving member mounted for free movement longitudinally thereof, and a control member mounted for automatic longitudinal movement thereof and rotary movement therewith, said control member in its longitudinal movement being adapted to contact the driving member and clamp the latter to the shaft for rotary movement therewith when such driving member is stopped in its longitudinal movement, said driving and control members being normally separate and free of each other and being provided with positive clutch means comprising a groove in one of said members and a cooperating rib in the other member, the driving faces of the groove and

rib being so made as to be in full contact when driving, said driving member having a free longitudinal movement with respect to the control member.

8. An engine starter drive including a rotatable shaft, a driving member mounted for free movement longitudinally thereof, and a control member mounted for automatic longitudinal movement thereof and rotary movement therewith, said control member in its longitudinal movement being adapted to contact the driving member and clamp the latter to the shaft for rotary movement therewith when such driving member is stopped in its longitudinal movement, said driving and control members being normally separate and free of each other and being provided with positive clutch means comprising a groove in one of said members and a cooperating rib in the other member, the sides of the rib extending convergently outwardly and the sides of the groove being parallel. 70 75 80 85 90

9. An engine starter drive including a rotatable shaft, a driving member mounted for free movement longitudinally thereof, and a control member mounted for automatic longitudinal movement thereof and rotary movement therewith, said control member in its longitudinal movement being adapted to contact the driving member and clamp the latter to the shaft for rotary movement therewith when such driving member is stopped in its longitudinal movement, said driving and control members being normally separate and free of each other and being provided with positive clutch means comprising a groove in one of said members and a cooperating rib in the other member, the driving faces of the groove and rib being so made as to be in full contact when driving, said groove being materially wider than the rib, said driving member having a free longitudinal movement with respect to the control member. 110

10. An engine starter drive including a rotatable shaft, a driving member mounted for free movement longitudinally thereof, and a control member mounted for automatic longitudinal movement thereof and 115 rotary movement therewith, said control member in its longitudinal movement being adapted to contact the driving member and clamp the latter to the shaft for rotary movement therewith when such driving member is stopped in its longitudinal movement, said driving and control members being normally separate and free of each other and being each provided with a disk, said disks being arranged in parallel planes, and 120 having complementary clutch means on 125 their adjacent faces.

11. An engine starter drive including a rotatable shaft, a driving member mounted for free movement longitudinally thereof, 130

- and a control member mounted for automatic longitudinal movement thereof and rotary movement therewith, said control member in its longitudinal movement being 5 adapted to contact the driving member and clamp the latter to the shaft for rotary movement therewith when such driving member is stopped in its longitudinal movement, said driving and control members being 10 normally separate and free of each other and being each provided with a disk, such disks being arranged in parallel planes and one of them having a transverse groove and the other a transverse rib, said groove and 15 rib being located on the adjacent faces of the two disks and adapted to cooperate with each other.
12. An engine starter drive including a rotatable shaft, a driving member mounted 20 for free movement longitudinally thereof, and a control member mounted for automatic longitudinal movement thereof and rotary movement therewith, said control member in its longitudinal movement being 25 adapted to contact the driving member and clamp the latter to the shaft for rotary movement therewith when such driving member is stopped in its longitudinal movement, said driving and control members being 30 provided with positive clutch means comprising a groove in one of said members and a cooperating rib in the other member, the groove being greater in depth than the rib in thickness.
13. An engine starter drive including a rotatable driving shaft, a driving member mounted for free movement longitudinally thereof, and adapted to engage a member 35 of the engine to be started, a control member mounted for automatic longitudinal movement of such shaft and rotary movement therewith, and means for releasing the pressure of the control member against the driving member in case of stoppage of such 40 driving member at an intermediate point in its longitudinal movement.
14. An engine starter drive including a rotatable driving shaft, a driving member mounted for free movement longitudinally 45 thereof, and adapted to engage a member of the engine to be started, a control member mounted for automatic longitudinal movement of such shaft and rotary movement therewith, and means for causing end 50 movement of the control member backwardly to release the pressure of the driving member against the engine member in case of stoppage of such driving member thereby.
15. An engine starter drive including a 55 rotatable driving shaft, a driving member mounted for free movement longitudinally thereof, and adapted to engage a member of the engine to be started, a control member mounted for automatic longitudinal movement of such shaft and rotary movement 60
- therewith, and means for rotating the control member backwardly to release the pressure of the control member against the driving member in case of stoppage of such driving member at an intermediate point in its longitudinal movement. 70
16. An engine starter drive including a rotatable driving shaft, a driving member mounted for free movement longitudinally thereof, and adapted to engage a member 75 of the engine to be started, a control member mounted for automatic longitudinal movement of such shaft and rotary movement therewith, and means including a torsion spring cooperating with said shaft 80 adapted to rotate such shaft backwardly and thereby cause a backward end movement of the control member to release the pressure of the control member against the driving member in case of stoppage of such 85 driving member at an intermediate point in its longitudinal movement.
17. An engine starter drive including a rotatable driving shaft, a driving member mounted for free movement longitudinally 90 thereof, and adapted to engage a member of the engine to be started, a control member mounted for automatic longitudinal movement of such shaft and rotary movement therewith, and means for releasing the pressure of the control member against the driving member in case of stoppage of such 95 driving member at an intermediate point in its longitudinal movement, said means including a clutch between the driving and control members and an element for causing backward movement of the control member in 100 said case.
18. An engine starter drive including a rotatable driving shaft, a driving member mounted for free movement longitudinally 105 thereof, and adapted to engage a member of the engine to be started, a control member mounted for automatic longitudinal movement of such shaft and rotary movement therewith, and means for releasing the pressure of the control member against the driving member in case of stoppage of such 110 driving member at an intermediate point in its longitudinal movement, said means including a clutch between the driving and control members and a torsion spring acting on said shaft to rotate it backwardly and thereby cause a backward end movement of the control member in said case. 115
19. An engine starter drive including a rotatable driving shaft, a driving member mounted for free movement longitudinally 120 thereof, and adapted to engage a member of the engine to be started, a control member mounted for automatic longitudinal movement of such shaft and rotary movement therewith, and means for releasing the pressure of the control member against the driving member in case of stoppage of such 125
- 130

driving member at an intermediate point in its longitudinal movement, said means including a clutch between the driving and control members comprising grooves and 5 ribs on said latter two members, the grooves being wider than the ribs, and also including an element for causing backward movement of the control member in said case.

20. An engine starter drive including a 10 rotatable driving shaft, a driving member mounted for free movement longitudinally thereof, and adapted to engage a member of the engine to be started, a control member mounted for automatic longitudinal movement of such shaft and rotary movement therewith, and means for releasing the pressure of the control member against the driving member in case of stoppage of such driving member at an intermediate point in its longitudinal movement.

21. An engine starter drive including a 15 rotatable screwshaft, a pinion mounted for free movement longitudinally thereof, for engagement with a member of the engine to be started, a control member threaded on the shaft and adapted to control the advance longitudinal movement of the pinion and to clamp the same to the shaft for rotary movement therewith, clutch means 20 between the pinion and driving member, and means for rotating the shaft backwardly and thereby move the control member backwardly to release the pressure of the pinion against the engine member in 25 case of end to end abutting thereof.

22. An engine starter drive including a 25 rotatable driving shaft, a driving member mounted for free movement longitudinally thereof, and adapted to engage a member of the engine to be started, a control member 30 mounted for automatic longitudinal movement of such shaft and rotary movement therewith, and a drive spring arranged in the line of transmission of power and 35 adapted to be wound up in the forward direction of rotation and also adapted, because of its stored up energy, to cause backward movement of the control member in case of stoppage of the driving member at 40 an intermediate point in its longitudinal movement.

23. An engine starter drive including a 45 rotatable driving shaft, a driving member mounted for free movement longitudinally

thereof, and adapted to engage a member of 55 the engine to be started, a control member mounted for automatic longitudinal movement of such shaft and rotary movement therewith, and automatic means for reversing the direction of rotation of the 60 shaft in case of stoppage of such driving member at an intermediate point in its longitudinal movement and thereby relieve it from the pressure of the control member.

24. An engine starter drive including a 65 rotatable driving shaft, a driving member mounted for free movement longitudinally thereof, and adapted to engage a member of the engine to be started, a control member mounted for automatic longitudinal movement 70 of such shaft and rotary movement therewith, and a torsion drive spring co-operating with the shaft and adapted to be wound up in the forward direction of rotation and by its stored up energy adapted 75 to reverse the direction of rotation of such shaft to thereby release the pressure of the control member against the driving member in case of stoppage of the latter at an intermediate point in its longitudinal move- 80 ment.

25. An engine starter drive including a 85 rotatable shaft, a driving member mounted for free movement longitudinally thereof, and a control member mounted for longitudinal movement thereof and rotary movement therewith and cooperating with the driving member to establish driving relation between the shaft and a member of the engine to be started, said two members being 90 capable of free angular movement when in normal position and of a limited angular movement in other positions.

26. An engine starter drive including a 95 rotatable driving shaft, a driving member mounted for free movement longitudinally thereof, and a control member mounted for longitudinal movement thereof and rotary movement therewith and cooperating with the driving member to positively displace 100 the driving member longitudinally to establish driving relation with a member of the engine to be started, and clutch means adapted to operatively connect the two members for positive driving when the 105 driving member is stopped in its longitudinal movement.

WILLIAM L. McGRATH.
